United States Patent Office

Des. 196,345
Patented Sept. 17, 1963

196,345

COAT HANGER

Arthur C. Rowland, East Grand Rapids, Mich., assignor to A. J. Krajewski Mfg. Co., Inc., Cranston, R.I., a corporation of Rhode Island

Filed May 3, 1961, Ser. No. 65,012

Term of patent 14 years

(Cl. D80—8)

FIGURE 1 is a side elevation of a coat hanger, showing my new design the opposite side thereof being substantially the same; and

FIG. 2 is an enlarged fragmentary perspective view thereof.

I claim:

The ornamental design for a coat hanger, substantially as shown and described.
